(57) **CLAIM**

The ornamental design for a tree-shaped foodstuff, as shown
and described.

DESCRIPTION

FIG. 1 is a bottom, front, and right side perspective view of
a first embodiment of a tree-shaped foodstuff;
FIG. 2 is a front elevation view thereof;
FIG. 3 is a back elevation view thereof;
FIG. 4 is a right elevation view thereof;
FIG. 5 left elevation view thereof;
FIG. 6 is a top plan view thereof;
FIG. 7 is a bottom plan view thereof;
FIG. 8 is a bottom, front, and right side perspective view of
a second embodiment of a tree-shaped foodstuff;
FIG. 9 is a front elevation view thereof;
FIG. 10 is a back elevation view thereof;
FIG. 11 is a right elevation view thereof;
FIG. 12 is a left elevation view thereof;
FIG. 13 is a top plan view thereof; and,
FIG. 14 is a bottom plan view thereof.

The dot-dash broken lines define the bounds of the claim,
forming no part of the claimed design. Any portion of the
article between those lines forms no part of the claimed
design.

1 Claim, 6 Drawing Sheets
